FLUID PRESSURE CONTROL DEVICE

George H. Sailers, Houston, Tex.

Application August 13, 1946, Serial No. 690,120

4 Claims. (Cl. 166—2)

1

The invention relates to a well device and more particularly to a device to be positioned within a well to control production thereof.

One of the objects of the invention is to provide a device to be positioned within a well and to act as a safety device therefor as a protection against careless handling at the surface controls, or any occurrence which accidentally releases tubing pressure.

A further object is to provide a device to prevent blowing out of the well and to keep the well under constant control.

Another object of the invention is to provide a device to maintain constant control over the well without interrupting the normal flowing of the well in its high stages as the pressures are somewhat balanced, but plays a vital part in maintaining control on the well throughout the later days of the well's declining life during which the well is inclined to surge.

A still further object of the invention is to maintain bottom hole pressure against the oil bearing formation throughout the life of the well, to prevent the well from heading, and to keep uniform pressure within the well.

A further object is to provide a device to act as a safety factor in wells being swabbed in that the device does not permit the well fluids to flow in from the formation too fast.

Another object is to provide a combination well flowing control device and wash tool that allows washing of the well by pumping fluid down into the well through the device.

Another object of the device is to provide in combination a flow control device and wash tool wherein the inlet screen for well fluid may be washed and cleaned by circulation of fluid down and out through the screen on the tool.

These and further objects will become apparent with a consideration of the following description and drawings wherein:

Fig. 1 is a vertical sectional view of a well device showing an embodiment of the invention;

Fig. 2 is an enlarged sectional view of a detail of the disclosed embodiment.

In Fig. 1, the device is denoted generally at 1 and is shown as extending downwardly from the swedge nipple 2 connected to the lower end of a string of tubing 4. Extending downwardly from the swedge nipple 2 is a pipe section 5 which terminates in the coupling 6 which in turn serves as the housing for the valve mechanism denoted generally as 7. A screen section 9 is threaded into the lower end of the coupling and serves as inlet for the well fluid to the interior

2

of the device. The bottom portion of the device is shown as terminating in a collar 10 which in turn has a closure member 11 therein that serves to segregate the interior 12 of the screen section 9 from the screen shoe 13 on the bottom of the device.

An elongated tubular member 15 has its lower end within the screen shoe 13 and passes upwardly through gland 16 in the closure member 11, the upper end of this member being threaded into the tubular member 17 proximate the valve assembly 7. A centering disc 18 fits slidably within screen 9 and is attached to tubular member 15 in any suitable manner, such as by welds 19.

As best seen in Fig. 2, the valve mechanism 7 is shown as comprising a valve body 25 threaded into the inner periphery of the coupling 6. This valve body serves as a barrier between the upper and lower portion of the tool as will be more fully described. The tubular extension 17 at the upper end of the member 15 is secured to this barrier or valve body by means of the threads 32 whereby a continuous passage is formed from the lower end of the tubular member 15 to the control bore 20 in the valve body.

A tapered seat 26 in the lower portion of the body 25 has an annular channel 27 therein, the ports 28 within this channel communicating with the passages 29 thereby providing passageways between the channel 27 and the chamber 30 above the valve 7 and within the section 5.

The valve 33 is slidable upon the extension 17 and a spring 34 is shown positioned in the recess 35 of valve 25 and the spring 34 normally retains the valve in spaced relation from the valve body.

A plurality of counterbored passages 38 in the valve 33 are provided with chokes 37, of suitable hardened material, threaded into the well side of valve 33 and such chokes and passages serve to pass the well fluid through the valve when it is in seating position upon the seat 26, as will be more particularly pointed out in the description of operation of the device.

A tubular extension 40 threaded into the body 25 at 41 constitutes an upper extension of the composite member 15, thus providing a continuous passage from the shoe screen 13 upwardly through the central bore 20 in the valve body and into chamber 30 of pipe section 5. The upper end of the extension in chamber 30 is terminated by a downwardly opening spring loaded relief valve 50. Immediately therebeneath a collar 51 threaded on extension 40 of composite member 15 serves as a stop for the disc valve

55

53, such valve being slideable on the extension 40. A spring 44 interposed between this disc valve and the valve body 25 normally retains the disc valve in an upward spaced relation from the valve body when the device is being used as a flow control mechanism in the well.

A screen pipe 42 threaded interiorly of the swedge nipple 2 and extending downwardly therefrom into chamber 30 serves as an outlet passage for wash fluid from the tubing 4 to the chamber 30 and thence into extension 40 of tubular member 15. This screen pipe also serves as inlet passengers for well fluid from the chamber to the tubing when it operates as a flow control device.

In operation the device is lowered into the well on the string of tubing 4 and is positioned proximate a productive formation.

If the well is flowing and it is desired that operation of the device serve primarily as a control 20 for the flow of the well, the device will operate as follows:—

Fluid from the formation enters the chamber 12 below the barrier, or valve body 25 through the screen section 9. During normal flowing of the well, the well fluid will flow upwardly around valve 33 into ports 26 communicating with passages 29 and thence out openings 29 around disc valve 53 into the chamber 30. The fluid then passes from chamber 30 through screen pipe 42 and into the tubing 4 beyond. It is to be noted that while the well is flowing under normal conditions, valve 33 is retained in spaced relation from the barrier, or valve body 25 by suitable means such as a spring 34. The flow of well fluid is thereby unrestricted through the barrier and into the tubing 4 beyond. If the rate of flow of the fluid becomes too great, then valve 33 will move upwardly and come in contact with seat 26 of body 25. The flow of well fluid will then be restricted by its passage through the chokes 37 of valve 33 before passing through the barrier 25. It seems apparent that the pressure necessary to seat the valve 33 by sliding it upwardly on extension 17 would be that pressure that exceeds the tension of spring 34 plus the force of gravity tending to retain the valve in its downward position. When the pressure on both sides of barrier 25 becomes approximately equal, the valve 33 will then move downwardly from seating position on the valve body and the flow of fluid will then move unrestricted as described above.

If it is desired to clean the screen section 9 by washing fluid down through the tool, wash fluid is pumped through the screen pipe 42 from tubing 4 and thence passes downwardly around the disc valve 53 and into the passages 29, out and around the valve 33 and from chamber 12, and out through the screen section 9 of the device. It is to be noted that the flow of wash fluid to clean the screen section 9 by passing wash liquid outwardly therethrough is the reverse of the flow of well fluid into the device.

If it is desired to operate the device to wash the well bore, wash fluid is pumped downwardly from the tubing 4 out screen pipe 42 and into the chamber 30 above the barrier. In such case pumping is carried out at such a rate that downward pressure of the pumped fluid upon the valve 53 causes the valve to move downwardly and compress the spring 44 therebeneath and thus seat upon the valve body 25. Such closure of the valve 53 prohibits the passing of wash fluid through the valve barrier 25 as above described.

The wash fluid then exerts sufficient pressure to unseat ball check valve 50 downwardly whereby wash fluid passes downwardly through the central bore 20 of valve body 25 and thence through the tubular member 15 to be discharged through screen shoe 13 in the bottom of the device. In this manner the wash liquid may be circulated into the well bore.

Broadly the invention comprehends a novel combination well control device and wash tool adapted to be positioned within a well to control the flow of fluids therein.

The invention claimed is:

1. A control and washing device for wells comprising, a housing, a barrier dividing the housing into separate upper and lower portions therein, there being a passage through said barrier, a hollow wash pipe independent of said passage and extending through said barrier to allow downflow of wash fluids through said barrier, an upwardly closing check valve in said pipe, an upwardly closing valve below said barrier surrounding said wash pipe and movable to close said passage upon an inflow of well fluid from below the barrier which is in excess of a predetermined rate of flow, and a valve on the upper side of said barrier to prevent downward flow of washing fluid through the first mentioned passage at greater than a predetermined rate, whereby the flow of fluids in the well is controlled.

2. A control and washing device for wells comprising, a housing, a barrier dividing the housing into separate upper and lower portions therein, there being a passage through said barrier, a hollow wash pipe independent of said passage and extending through said barrier to allow downflow of wash fluids through said barrier, an upwardly closing check valve in said pipe, an upwardly closing valve below said barrier surrounding said wash pipe and movable to close said passage upon an inflow of well fluid from below the barrier which is in excess of a predetermined rate of flow, and a valve on the upper side of said barrier to prevent downward flow of washing liquid through the first mentioned passage at greater than a predetermined rate whereby the flow of fluids in the well is controlled, said valve below the barrier having a leak passage therethrough whereby well fluid will be passed through said barrier to equalize the pressure in said housing above and below said barrier when said upwardly closing valve is closed, whereupon said upwardly closing valve will fall to open position to allow well fluids to pass unrestricted through said passage in said barrier and into said tubing.

3. A well control and washing device to be connected to a tubing comprising, a housing, a barrier dividing said housing into upper and lower portions, there being a passage through said barrier, a downwardly closing valve above said barrier for said passage, resilient means normally holding said valve in open position, a wash pipe extending through said barrier, an upwardly closing check valve in said wash pipe, said downwardly closing valve being normally open but movable to closed position by flow of fluid pumped downwardly through the housing at greater than a predetermined rate, whereby the pumped fluids pass downwardly through and are exhausted from said wash pipe at its lower end.

4. A well control and washing device comprising, a housing, a barrier in said housing dividing the housing into upper and lower portions, there being a passage through said barrier, said hous-

ing below the barrier comprising a screen section for the admission of well fluids, a downwardly closing valve above said barrier movable to close said passage, a wash pipe extending through said barrier and downwardly to a point below the screen section and open at its lower end, an upwardly closing check valve in said wash pipe, yieldable means to normally hold said downwardly closing valve open to admit a downward flow of pumped low velocity fluids through the barrier and outwardly through the openings in the screen section, but said downwardly closing valve being closable when the velocity of said fluid past said valve exceeds a predetermined rate whereby said fluid is then directed downwardly through said wash pipe.
